DESCRIPTION

U.S. PATENT DOCUMENTS

FIG. 1 is a top perspective view of the quad-hook for a steering wheel lock of the present invention;

D. 324,163	*	2/1992	Lo	.....	D8/331
D. 357,621		4/1995	Yang	.....	D8/343
D. 368,421		4/1996	Jensen, Sr.	.....	D8/331
D. 369,951		5/1996	Crittenden	.....	D8/331
D. 370,616		6/1996	Fard	.....	D8/331
3,690,131		9/1972	Davis	.....	70/203
5,197,308		3/1993	Pazik	.....	70/209
5,406,813	*	4/1995	Lo	.....	70/209
5,435,158	*	7/1995	Ta-Yung	.....	70/209
5,778,709		7/1998	Hsu	.....	70/209

FIG. 2 is a bottom perspective view of the quad-hook for a steering wheel lock of the present invention;

FIG. 3 is a top view thereof;

FIG. 4 is a bottom view thereof;

FIG. 5 is a left end view thereof;

FIG. 6 is a right end view thereof;

FIG. 7 is a side view thereof; and,

FIG. 8 is a side view thereof, opposite that of FIG. 7.

The portions shown in phantom lines are not part of the claimed invention, but are included to show environment. The phantom lines illustrate a feature such as a steering wheel lock to which the quad-hook can be attached.
